RESTRICTOR VALVES

Daniel S. Dickinson, Louisville, Ky., assignor to General Electric Company, a corporation of New York

Application November 14, 1952, Serial No. 320,379

2 Claims. (Cl. 137—505.13)

My invention relates to load limiting devices and more particularly to such devices used in connection with refrigeration apparatus for automatically limiting to a predetermined maximum the load on the driving motor.

Following an extended idle period of a refrigerator, such as during storage or shipping, the refrigerant pressure on the suction or normally low pressure side of the compressor and the refrigerating system employed for cooling the refrigerator rises considerably. During pull-down, or the period required by the compressor to come up to speed following an extended idle period, this high pressure on the suction side of the compressor results in considerable loading of the motor driving the compressor. Such heavy motor loading is encountered also during normal operation when the refrigerator is well stocked with heat laden items. One manner of coping with this situation is to provide the refrigerator with a motor large enough to operate easily under abnormally heavy loading conditions. This, however, would result in poor economy in space and materials and inefficient motor operation under normal conditions. From the standpoints of good economy in space and materials and high efficiency in motor operations, it is desirable to employ a small motor having a capacity just sufficient for driving the compressor satisfactorily under normal conditions. When such a motor is employed, it is essential to provide means for limiting to a predetermined maximum the pressure at the suction side of the compressor thereby to avoid overloading of the motor during pull-down or during starting of the compressor under abnormally heavy refrigerator loads.

The primary object of my invention is to provide a new and improved arrangement for avoiding overloading of a compressor motor by limiting to a predetermined maximum the pressure at the suction side of the compressor.

Further objects and advantages of my invention will become apparent as the following description proceeds and the features of novelty which characterize my invention will be pointed out with particularity in the claims annexed to and forming part of this specification.

In carrying out the objects of my invention, I provide a housing adapted for connection to the low pressure side of a compressor, porting means for admitting refrigerant into the housing and valve means cooperating with the porting means. The valve means includes a plunger, and when the pressure drop across the plunger exceeds a predetermined maximum, the porting means is rendered ineffective. Means tending to equalize pressure across the plunger is effective when the porting means is ineffective for decreasing the pressure drop below the predetermined maximum for thereby rendering the porting means again effective.

For a better understanding of my invention, reference may be had to the accompanying drawing in which

Fig. 1 is a schematic representation of a refrigerating system.

2

Fig. 2 is an end view partially broken away of the refrigerating unit shown in Fig. 1.

Fig. 3 is an enlarged sectional elevation view of a portion of Fig. 2 showing details of the load limiting device.

5 And Fig. 4 is an enlarged sectional elevation view of a second embodiment of the load limiting device.

In Fig. 1 there is shown a refrigerating system including a condenser 1, an evaporator 2 and a refrigerating unit 3. The flow of refrigerant from the condenser to the evaporator is controlled by a capillary tube 4. Compressed refrigerant is supplied to the condenser 1 from the refrigerating unit 3 through a conduit 5 and vaporized refrigerant is returned to the refrigerating unit from the evaporator 2 through a conduit 6.

15 As better seen in Fig. 2, the refrigerating unit 3 comprises a hermetically sealed case 7 and a compressor 8 arranged in the case. The compressor 8 is driven by a suitable motor (not shown). Through the conduit 6 the case 7 receives vaporized refrigerant from the evaporator 20 2. The vaporized refrigerant passes to the suction side of the compressor 8 through a load limiting device 9 and an intake muffler 10 also arranged within the case.

25 Referring now to Fig. 3, the load limiting device 9 includes a housing 11. Provided in the upper portion of the housing 11 is a refrigerant outlet 12. A tube 13 connects the outlet 12 of the housing 11 with the intake muffler 10. Tubes 15 and 16 connect the intake muffler 10 with the suction or low pressure side of the compressor 8. Thus the housing 11 is connected to the low pressure side of the compressor 8. Compressed refrigerant is discharged from the compressor 8 through a conduit 17 into an exhaust muffler 18 and passes from the exhaust muffler to the condenser 1 through the conduit 5.

30 As seen in Figs. 2 and 3, the load limiting device 9 includes porting means for admitting refrigerant from the case 7 into the housing 11. The porting means comprises a conduit 19 extending transversely through the lower portion of the housing 11 and having both extremities open for receiving refrigerant from the case 7. 40 To increase the effectiveness of the conduit 19 in admitting refrigerant into the housing from the case, the conduit is so formed that one extremity designated 20 extends horizontally while the other extremity designated 21 extends vertically. Additionally, both extremities 20 and 21 are flattened slightly.

45 In the housing 11, the conduit 19 is formed with a reduced portion 22. Formed in the reduced portion 22 for providing communication between the conduit and the housing is a pair of opposed orifices 23. Further included in the load limiting device 9 is valve means for cooperating with the porting means. The valve means includes a plunger 24 adapted for operating in the housing between the outlet 12 and the conduit 19. The plunger 24 is weighted and fits loosely in the housing 11. Formed adjacent each end of the plunger 24 is a peripheral groove 25. Provided for fitting in the peripheral grooves 25 are spring wire members 26, each of which is formed with a plurality of spaced apart radial projections 27. The projections 27 slidely engage the interior walls of the housing 11 and are effective for maintaining a predetermined clearance or space, indicated by 30, between the plunger 24 and the housing 11. The space 30 tends to equalize pressure across the plunger. In the arrangement described to this point, the plunger 24 is adapted for lifting from and falling to the position thereof shown in Fig. 3 in accordance with the pressure drop across the plunger.

55 In the underside of the plunger 24 is formed a downwardly opening recess 31. The recess 31 includes a cylindrical surface 32 at the bottom and a conical surface 33 at the mouth thereof. Secured to the plunger

24 at the bottom of the recess 31 and extending toward the orifices 23 is a flexible element or wire 34. Suitably secured to the free end of the wire 34 and extending through the orifices 23 is a member or valve stem 35. For a purpose which will be explained in detail herein-after the recess 31 and the wire 34 render the valve stem 35 movably outwardly from the vertical axis of the plunger. Formed on the valve stem 35 is a pair of spaced apart spherical portions 36. One of the spherical portions 36 is disposed in the conduit 19 and is adapted for cooperating with the upper one of the orifices 23. The other of the portions 36 is disposed below the conduit 19 and cooperates with the lower one of the orifices 23. It will be seen that while I prefer employing opposed orifices in the conduit and a pair of spherical portions on the valve stem, satisfactory performance of the device could be obtained with a single orifice and a single cooperating spherical portion.

The weight of the plunger 24 biases the valve stem 35 to the position thereof shown in Fig. 3, in which position the spherical portions 36 are rendered unrestrictive with respect to refrigerant flow from the conduit 19 through the orifices 23 and into the housing 11. It will be seen that the plunger and the valve stem may be biased to the position of Fig. 3 by a spring if it is not desired to rely on the weight of the plunger or if the housing is to be mounted horizontally and a weighted plunger cannot be employed.

When the pressure of refrigerant in the evaporator 2 and therefore, in the case 7, increases and results in a pressure drop across the plunger 24 sufficient for overcoming the biasing effect of the plunger, the plunger lifts and, through the flexible connection 34 between the plunger and the valve stem, moves the spherical portions 36 of the valve stem toward the orifices 23. In accordance with the pressure drop across the plunger 24 and the amount of the resultant lift of the plunger the flow of refrigerant through the orifices 23 is restricted by the spherical portions 36, or in other words, the effectiveness of the porting means in admitting refrigerant into the housing for conduction to the compressor is varied.

When the pressure drop across the plunger 24 exceeds a predetermined maximum, as will be the case during pull-down or starting under unusually heavy loading of the refrigerator, the amount of lift of the plunger 24 will be such as to move the spherical portions 36 into the orifices 23 for thereby closing the orifices. With the orifices 23 closed in this manner, the refrigerant is no longer admitted into the housing 11 from the case 7 and the pressure at the suction side of the compressor, and therefore, the load on the motor driving the compressor, are limited to a predetermined maximum. The compressor 8, however, continues to operate and draws refrigerant across the plunger through the space 30. Thus, the pressure drop across the plunger is slowly reduced below the predetermined maximum and the plunger slowly falls toward the position of Fig. 3. The plunger in falling causes the spherical portions of the valve stem to move slowly downwardly out of the orifices 23 whereby the orifices are again rendered effective for admitting refrigerant into the housing 11 from the conduit 19. The amount of refrigerant admitted into the housing will be sufficient to cause the plunger 24 to assume, and be maintained in during subsequent normal operation, a lifted position in which the spherical portions 36 restrict to the predetermined maximum the amount of refrigerant flow through the orifices 23.

It will be seen that the mentioned predetermined maximum to which the device 9 limits the flow of refrigerant to the compressor is dependent upon, and may be varied by varying, one or more of a number of factors. These factors are the weight and area of the plunger 24, the clearance 30 between the plunger and the housing, and the clearances between the spherical portions 36 on the

valve stem 35 and the orifices 23. Additionally, while I have shown the spherical portions 36 as being so spaced apart that they would simultaneously close and simultaneously open their respective orifices, it will be seen that they may be so spaced as not to close and open the orifices simultaneously for thereby varying the flow restricting characteristics of the device.

In the device 9 the flexible connection between the plunger 24 and the valve stem 35, as effected by the flexible wire 34, and the tapered surfaces of the spherical portions 36 are effective for affording self-alignment of the valve stem and the spherical portions thereon with the orifices 23. This self-alignment feature eliminates the need for accurately machined components and, consequently, results in a cost reduction. While I have shown the portions 36 as being spherical, it will be seen that they may be of any configuration which provides tapering surfaces for cooperating with the orifices 23. For instance, they could be conical.

20 Provided for minimizing jet reaction of refrigerant flowing through the upper one of the orifices 23 on the interior surfaces of the recess 31 is a baffle member 37. The baffle member 37 is formed with a plurality of horizontal radial tabs 38. The tabs 38 rest on and are 25 suitably secured to an interior shoulder 39 formed in the housing 11. Also formed on the baffle member 37 and alternating with the horizontal tabs 38 are upwardly bent tabs 40. The upwardly bent tabs 40 provide a seat for the plunger 24 when the plunger is in its downward position. Additionally, the tabs 40 permit the passage of 30 refrigerant from the lower portion of the housing 11 to the upper portion. Centrally formed in the baffle member 37 is an aperture 41. The aperture 41 permits extension of the valve stem 35 through the baffle 37 and is 35 sufficiently large for permitting lateral movement of the valve stem 35 necessary to the self-alignment of the spherical portions on the stem with the conduit orifices.

In Fig. 4 there is shown a second embodiment of my load limiting device generally designated 45. The device 40 45 comprises a housing 46 including an outlet 47 formed in the upper portion of the housing, and porting means comprising a plurality of radially spaced lateral intake ports 48. As seen in Fig. 4, the intake ports 48 may be key-hole shaped. The device 45 is adapted for being 45 arranged in the case 7 of the refrigerating unit 3 in the same manner as the above described first embodiment 9. A tube 49 is provided for connecting the outlet 47 of the housing 46 to the intake muffler 10. The device 45 further comprises valve means including a plunger 50 50 adapted for operating in the housing 46 and cooperating with the porting means. The plunger 50 is weighted and fits loosely in the housing. The weight of the plunger 50 biases the plunger for being seated in the lower end of the housing 46 in the manner shown in Fig. 4. In this 55 form of my invention, also, the plunger instead of being weighted could be biased by a spring.

The plunger 50 is formed to include a reduced intermediate portion 51. When the plunger 50 is seated in the bottom of the housing 46 in the manner shown in 60 Fig. 4, the reduced portion 51 is in register with the intake ports 48. The reduced portion 51 divides the plunger into an upper or first plunger portion 52 and a spaced apart second or lower plunger portion 53. The upper portion 52 is adapted for operating between the outlet 47 and the intake ports 48, and the portion 53 is adapted for cooperating with the lateral ports 48 to determine the refrigerant flow therethrough. Provided for affording refrigerant flow across the upper portion 52 of the plunger 50 is a refrigerant passage 54. Provided for affording 65 refrigerant flow across the lower portion 53 of the plunger 50 is a bleeder passage 55. As pointed out above, the plunger 50 fits loosely in the housing 46. In this manner, a clearance 56 is provided between the plunger and the housing. The refrigerant passage 54 tends to equalize 70 pressure across the upper portion 52; the bleeder passage 75

55 tends to equalize pressure across the lower portion 53; and the passages 54 and 55, together with the clearance 56, all tend to equalize pressure across the plunger 50 as a whole. As a result, refrigerant entering the housing 46 through the lateral intake ports 48 tends to flow past the plunger and through the outlet 47 and the tube 49 to the compressor.

The weight of the plunger 50 biases the plunger to the position thereof shown in Fig. 4, in which position the lower portion 53 is rendered unrestrictive with respect to refrigerant flow through the ports 48 and into the housing 46 for conduction to the compressor 8. When the pressure of refrigerant in the case 3 increases and results in a pressure drop across the plunger sufficient for overcoming the biasing effect of the plunger, the plunger lifts. In accordance with the pressure drop across the plunger 50 and the amount of resultant lift of the plunger, the flow of refrigerant through the lateral ports 48 is restricted by the lower portion 53 of the plunger. Or in other words, the lower portion 53 of the plunger varies the effectiveness of the porting means in admitting refrigerant into the housing for conduction to the compressor. During pull-down, or starting under unusually heavy loading of the refrigerator, the pressure drop across the plunger 50 exceeds a predetermined maximum and the plunger lifts to a point where the lower portion 53 effectively closes the lateral ports 48. With the lateral ports 48 closed in this manner, refrigerant is no longer admitted into the housing 46 from the case 7 and the pressure at the suction side of the compressor, and therefore, the load on the motor driving the compressor, are limited to a predetermined maximum. Operation of the compressor 8, however, draws refrigerant across the plunger 50 through the refrigerant passage 54 and the bleeder passage 55, and in this manner the pressure drop across the plunger is slowly reduced below the predetermined maximum. The plunger slowly falls toward the position of Fig. 4 and the lower portion 53 thereof opens the lateral ports 48 again for admitting refrigerant into the housing 46 from the case 7. The amount of refrigerant admitted into the housing will be sufficient to cause the plunger 50 to assume, and be maintained in during subsequent normal operation, a lifted position in which the lower portion 53 thereof restricts to the predetermined maximum the amount of refrigerant flow through the intake ports 48.

It will be seen that the mentioned predetermined maximum to which the device 45 limits the flow of refrigerant to the compressor is also dependent upon, and may be varied by varying, one or more of a number of factors. In the device 45 these factors are the weight and area of the plunger 50, the diameters of the passages 54 and 55, the clearance 56 between the plunger and the housing, and the number of and configuration of the lateral intake ports 48.

Provided for minimizing side thrust of the plunger 50 in the housing 46 is a plurality of spaced apart peripheral grooves 57 formed in both the upper and lower portions 52 and 53, respectively, of the plunger 50. The grooves 57 minimize side thrust by equalizing pressure about the plunger 50.

While I have shown and described specific embodiments of my invention, I do not desire my invention to be limited to the particular forms shown and described and I intend by the appended claims to cover all modifications within the spirit and scope of my invention.

What I claim as new and desire to secure by Letters Patent of the United States is:

1. A pressure valve for limiting to a predetermined maximum the pressure of gas passing therethrough comprising a housing having outlet porting means and inlet porting means, the latter including a conduit extending transversely in said housing, said conduit including a pair of inlet orifices for admitting gas from said conduit into said housing, and valve means in said housing, said valve

means including a weighted plunger slidable in said housing between said inlet and outlet porting means, spacing means maintaining a space between said plunger and said housing to provide for the flow of gas therebetween so that gas may flow to said outlet porting means and also so that there is the tendency for gas pressure across said plunger to equalize, said plunger having walls defining a recess extending upwardly from the bottom of said plunger, a flexible element in said recess secured to said plunger, a valve stem secured to said flexible element having a pair of spaced spherical portions, said spherical portions being movable into said orifices for restricting the flow of gas therethrough, said flexible element and the contours of said spherical portions affording self-alignment of said spherical surfaces with said orifices, said spherical surfaces being biased by the weight of said plunger to positions wherein they do not restrict the gas flow through said orifices, and moved to positions to restrict gas flow through said orifices by said plunger in accordance with the pressure drop across said plunger, and finally to positions to close said orifices when said pressure drop exceeds a predetermined maximum, said space between said plunger and housing being effective when said orifices are closed for decreasing said pressure drop below said predetermined maximum thereby to permit said plunger to move to reopen said orifices.

2. A pressure valve for limiting to a predetermined maximum the pressure of gas passing therethrough comprising a housing having outlet porting means and inlet porting means, the latter including a conduit extending transversely in said housing, said conduit including a pair of opposed inlet orifices for admitting gas from said conduit into said housing, and valve means in said housing, said valve means including a weighted plunger movable between said inlet and outlet porting means, spacing means maintaining space between said plunger and said housing, said space providing for the flow of gas around said plunger so that gas may flow to said outlet porting means and so that there is the tendency for gas pressure across said plunger to equalize, said plunger having walls defining a recess in the underside of said plunger, a flexible element in said recess secured to said plunger, said flexible element extending toward said orifices, a valve stem secured to said flexible element, said valve stem including a pair of spaced spherical portions, said spherical portions being movable into said orifices for restricting the flow of gas through said orifices, said flexible element and the contours of said spherical portions affording self-alignment of said spherical portions with said orifices, said spherical portions being biased to open position with respect to said orifices by the weight of said plunger and moved to gas flow restricting positions with respect to said orifices by said plunger in accordance with the pressure drop across the plunger, and finally to positions to close said orifices when said pressure drop exceeds a predetermined maximum, said space between said plunger and housing being effective when said orifices are closed for decreasing said pressure drop below said predetermined maximum thereby to reopen said orifices, and a baffle element within said housing adjacent said plunger for minimizing jet reaction against said plunger of gas flowing through said orifices.
